UNITED STATES PATENT OFFICE

JOHN L. McMILLAN, OF SYRACUSE, NEW YORK, ASSIGNOR TO McMILLAN BOOK COMPANY, OF SYRACUSE, NEW YORK, A CORPORATION OF NEW YORK

SHIFTING PLATE FOR LOOSE LEAF BINDERS

Application filed April 15, 1929. Serial No. 355,261.

This invention relates to a new and improved shifting plate for loose leaf binders.

In using loose leaf binders in the conduct of a business or other enterprise, it is frequently necessary to transfer portions of the sheets in a loose leaf binder to another loose leaf binder. In order to do this, it is of course, necessary to open the prongs, rings or posts of the binder to permit the removal therefrom of the sheets which it is desired to transfer. It is also, of course, necessary to then open the binder to which the sheets are to be transferred so that the same may be placed upon the prongs, rings or posts of the

15 second binder.

Inasmuch as loose leaves are confined in a binder by virtue of the fact that they are provided with apertures along one edge through which the prongs or rings of the binder extend, it is necessary, when inserting a sheet or sheets into a binder that the apertures in the sheets be placed in exact registration with the prongs or rings which are to receive them.

In the case of a single sheet, this is comparatively an easy procedure, but when it is desired to place a plurality of sheets in a binder, it is difficult to manually arrange all of the sheets so that corresponding apertures in the sheets will be in registration with each other to permit the passage therethrough of the prongs or rings of the binder into which they are to be placed.

The main object of my invention is to provide a device by the use of which a plurality of sheets may be removed from a binder and maintained with the corresponding apertures in the sheets in registration, so that such sheets may be placed upon the prongs or rings of a second binder with a minimum of effort and care.

Another object is to provide a device to aid in transferring sheets from one binder to another, which may be used with different types of binders if desired.

Other objects and advantages relate to the size, shape and arrangement of parts, all as will more fully appear from the following description taken in connection with the accompanying drawings, in which:

Figure 1 is a perspective view of my shifting plate.

Figure 2 is a section on line 2—2, Figure 1.

Figure 3 is a section on line 3—3, Figure 1.

Figure 4 is a perspective view, partially broken away, of a prong book in the open position, and with my device in the proper relative position to be used therewith.

My shifting plate 1 consists of a flat body portion 2, preferably rectangular in shape and of a material which is substantially stiff, to permit the easy handling thereof when loose leaves are in position on the shifting plate.

On one longitudinal edge of the body portion 2, I provide a plurality, in this case shown as 7, of vertically extending posts 3 in longitudinal spaced relation. The position and spacing of the posts 3 is such that they are adapted to be inserted into correspondingly spaced apertures in loose leaves.

On the same edge of the body portion 2, which carries the posts 3, I provide a plurality of apertures 4, intermediate said posts and in alignment therewith. In the embodiment here shown, I have provided three apertures 4 between each pair of adjacent posts 3 and a single aperture at each end of the body portion 2, beyond the end posts 3.

The apertures 4 are of a size and shape and so positioned that certain of them will register with the prongs or rings of a loose leaf binder, so that when the posts 3 are inserted into apertures in the loose leaves in a binder, the ends of the prongs or rings of the binder will simultaneously enter certain of the apertures 4, so that the shifting plate 1 may be moved downwardly onto the upper surface of the topmost sheet in the binder.

For the purpose of explaining the operation of my device in conjunction with a loose leaf binder, I have here shown in Figure 4 a loose leaf binder 5, of the type usually termed a prong binder having opposed hinged back members 6 and 7, upon which are carried a plurality, in this case shown as nine on member 6, of prongs 8 in longitudinally spaced relation, and a plurality, in this case shown as eight, of prongs 10.

9 on member 7 in longitudinally spaced relation. Prongs 8 are in staggered relation to prongs 9.

- The binder 5 is also provided with a cover 10 hingedly connected to back member 7, and with an opposing cover 11 hingedly connected to back member 6. I also show in position on prongs 9 a plurality of loose leaves 12. The loose leaves 12 are provided 10 on one edge with a plurality of apertures 13, in longitudinally spaced relation, and so positioned as to permit the passage therethrough of prongs 9 and prongs 8 when the book is in the closed position.
- 15 When it is desired to transfer sheets 12 on binder 5 to another binder, not shown, binder 5 is opened to the position shown in Figure 4. The shifting plate 1 with the posts 3 extending downwardly is then placed in 20 position on the uppermost of sheets 12, with the posts 3 extending downwardly into apertures 13 and with the prongs 9 extending upwardly through certain of the apertures 4. When the shifting plate 25 1 is in the last-described position, the operator grasps the leaves 12 which he desires to transfer and holds them in juxtaposition and with the topmost one against the under surface of shifting plate 1. The 30 loose leaves 12 and the shifting plate 1 are then raised simultaneously upwardly off of the prongs 9 and are then carried to a second loose leaf binder, which has been placed in the open position to receive the sheets 12.
- 35 The prongs of the second binder, not shown, are then inserted through apertures 13 in loose leaves 12 and through apertures 4 in shifting plate 1 and the loose leaves 12 allowed to move downwardly on such prongs.
- 40 The shifting plate 1 is then moved upwardly from the prongs of the second binder and the prongs of the second binder are then moved to the closed position.

It will be appreciated that when a plurality of loose leaves 12 are on the posts 3 of shifting plate 1 they may be moved from place to place retaining the corresponding apertures 13 in the loose leaves 12 always in registration, so that the insertion into them 50 of the prongs of a binder, in one operation, is comparatively simple and easy.

It will also be appreciated that the number and arrangement of the posts 3 on the shifting plate 1 may be varied as desired, as 55 may the number and position of the apertures 4 in shifting plate 1.

It will also be appreciated that by the proper positioning of posts 3 and apertures 60 4 in shifting plate 1 the shifting plate 1 may be adapted to be used with different types of binders, whether prong, ring or posts.

It will also be appreciated that the length 65 and exact shape of the posts 3 may be varied depending upon the maximum number of

loose leaves 12 which it may be desired to transfer in one operation.

It will also be understood that the materials of which my shifting plate are made may be varied to a considerable extent, for 70 although I have shown and described a specific structure and form of parts, as illustrative of an embodiment of my invention, I do not desire to restrict myself to the exact size, shape or relation of parts as various changes 75 may be made within the scope of the appended claims.

I claim:

1. In a device of the class described, a substantially flat body portion, a plurality 80 of vertically extending posts affixed to one edge of the body portion in spaced relation and adapted to enter apertures in loose leaves, and said body portion having apertures with unbroken edges near one edge in 85 alignment with the posts and adapted to receive the prongs of a loose leaf binder.

2. In a device of the class described, a substantially flat body portion, a plurality of 90 vertically extending posts affixed to one edge of the body portion in spaced relation and adapted to enter apertures in loose leaves, and said body portion having a plurality of 95 apertures with unbroken edges near one edge and intermediate adjacent posts and in alignment therewith and adapted to receive the prongs of a loose leaf binder.

In witness whereof I have hereunto set my hand this 14th day of March, 1929.
